UNITED STATES PATENT OFFICE.

JACOB H. ROBEY, OF HARTFORD, INDIANA.

GRAVE COFFIN-RECEPACLE.

SPECIFICATION forming part of Letters Patent No. 324,167, dated August 11, 1885.

Application filed May 12, 1885. (No model.)

To all whom it may concern:

Be it known that I, JACOB H. ROBEY, a citizen of the United States, residing at Hartford city, in the county of Blackford and State 5 of Indiana, have invented new and useful Improvements in Grave Coffin - Receptacles, of which the following is a specification.

This invention relates to certain new and useful improvements in burial or grave coffin-receptacles; and it consists in making the same of plastic or cementitious sections, the body or main receptacle and the lid or covering in separate and distinct pieces, with an opening near one end of the lid or cover, 15 protected by a glass or transparent substance molded or embedded therein; also, connecting with said cover a tubular column, through which the remains may be viewed, the object being to provide a cheap, durable, and water- 20 proof molded stone vault or receptacle to replace the common wooden box now in general use as a receptacle for the coffin, or the expensive metallic caskets, which in course of time corrode and become worthless.

25 In the accompanying drawings, Figure 1 represents a longitudinal section of my improved grave-receptacle; Fig. 2, a similar view of the same, having a surface-view column; and Fig. 3, a cross-section taken on 30 the line *xx* of Fig. 1, and Fig. 4 a view in perspective of the grave-receptacle shown in Fig. 2.

The grave coffin-receptacle is formed of a plastic material of such a nature as to resist the destructive influence of moisture and air. 35 The compound which I have found best suited for the purpose at a minimum expenditure consists of the ingredients proportionally compounded, as follows: Cement or water 40 lime, thirty-three and one-third per cent.; clear gray sand, fifty-one and two-thirds per cent.; calcined plaster, fifteen per cent. These should be thoroughly mixed with water to the proper consistency, and when set forms 45 an artificial-stone substance which is not susceptible to change under the influence of either air or moisture.

The receptacle A, made in any approved way of the above material, has a groove, B, 50 formed in its upper edge to receive a tongue, *c*, of the lid C, which latter is made of a sin-

gle piece with an opening, D, near one end protected by a glass or transparent substance, *d*, embedded or molded in the lid. The opening is preferably elliptical in form to correspond with the contour of a human face. A 55 rim or beading, E, surrounds this opening, and is rabbeted on its interior side, forming a shoulder, *e*.

The receptacle is made of varying sizes, 60 and may be used to receive the coffin only or the body, as desired. The sides and top may be paneled and embellished to suit varying tastes.

To render the joined sections water and air 65 tight, a layer of cementitious material is interposed between the lid and receptacle, which at the same time serves as a binding medium to hold the two parts together.

When the receptacle is buried beneath the 70 ground, a tubular column, H, rests upon the rim E of the lid, and is provided with a tongue or bead, *h*, to pass within the same and rest upon the rabbet *e*, the walls of which are flush with the interior wall of the casing H. 75 To keep out moisture the two are bonded by cement. The column H conforms to the shape of the opening in the lid and tapers from the same to its outer end, which terminates at any desired distance from the surface of the ground, 80 and is provided with a removable cap, I, having a rim, *i*, extending over, down, and around its sides, and a center, *j*, extending within the casing, thus effectually keeping out 85 wet and dust.

The column H is used only in such cases when it is desired to view the remains, and it may be replaced by a shouldered cap, J, having a rim, *l*, and center *m* to enter and fill the interior of the opening D' within the lid, above 90 the glass *d*.

I claim—

1. The herein-described water-proof air-tight burial receptacle, consisting of the receptacle, the lid having an opening surrounded 95 by a raised rabbeted rim, a glass cover for said opening molded in said lid below the rim, and a rimmed cap fitting within the raised rabbeted rim above the glass, the three parts being joined and sealed by cement, as shown 100 and described.

2. The water-proof air-tight burial-recep-

tacle consisting of the receptacle and a lid having an opening surrounded by a raised rabbeted rim, a glass cover for said opening molded in said lid below the rim, in combination with a removable tubular column having a tongue, *h*, fitted within the rabbeted rim, and a removable rimmed cap fitting over and outside of the upper end of said column, the said parts being joined, as shown and described.

In testimony whereof I have hereunto set my hand in the presence of two subscribing witnesses.

JACOB H. ROBEY.
